UNITED STATES PATENT OFFICE.

JESSE D. LANGDON, OF WATERVILLE, WASHINGTON.

FUEL-VAPORIZING SYSTEM FOR INTERNAL-COMBUSTION ENGINES.

1,350,413.

Specification of Letters Patent. Patented Aug. 24, 1920.

Application filed June 30, 1917. Serial No. 178,016.

To all whom it may concern:

Be it known that I, JESSE D. LANGDON, a citizen of the United States, residing at Waterville, in the county of Douglas and 5 State of Washington, have invented certain new and useful Improvements in Fuel-Vaporizing Systems for Internal-Combustion Engines; and I do hereby declare the following to be a full, clear, and exact description of the invention, such as will enable others skilled in the art to which it appertains to make and use the same.

My invention relates to a fuel vaporizing system for internal-combustion engines, and 15 has among its several objects the provision of a device associated with the water cooling system of an engine so as to utilize the heat units of the cooling system to vaporize fuel oils other than those normally used 20 through the carbureter and for commingling the additional vaporized fuel with the normal vaporized fuel in the intake manifold of the engine.

Among other objects of this invention is 25 to combine with the additional vaporized fuel or fuels a certain proportion of steam or water or both from the water cooling system of the engine to humidify the fuel and prevent the formation of carbon, and a 30 further provision of means for automatically supplying the additional fuel or fuels and water to the device and the water cooling system of the engine, and to also prevent pressure forming in the water cooling system.

A further object of this invention is to produce a device of this character consisting of few parts and simple in construction, efficient and durable, economical to manufacture, and which can be readily installed 40 in any of the internal combustion engines now in use or built in an engine during its course of manufacture.

These and other objects and advantages 45 will more fully appear as the nature of the invention is more clearly understood from the following description taken in connection with the accompanying drawings wherein there is disclosed one embodiment 50 of the invention, but which is susceptible to numerous variations and alterations in the form, construction, and arrangement of the parts to meet the exigencies of the case without departing from the spirit of the invention or exceeding the scope of the 55 claims.

In the drawings:

Figure 1 is a side view of an engine, showing the invention in applied operative position thereon.

Fig. 2 is a fragmentary side view of the upper portion of the radiator of the engine and the invention, shown partly broken away and partly in section, and showing the detail construction of this part of the invention.

Referring to the drawings, wherein similar reference characters denote corresponding parts throughout the several views, 1 denotes the engine, 2 the intake manifold, 70 3 the carbureter, 4 the radiator, 5 the filler nipple or steam dome, and 6 the overflow pipe having its upper end within the steam dome 5 and extending downwardly therefrom and to the exterior of the radiator 4. 75 The foregoing parts constitute the usual engine construction.

Supported upon the inner side of the radiator 4 by the upper pipe 7 and the lower pipe 8 is the container 9 having communication with the upper interior portion of the radiator 4 through the medium of the supporting and connecting pipes 7 and 8. The container 9 is preferably positioned upon the radiator 4 in such a manner 80 that the lower portion of the container will lie below the normal water level in the radiator 4 as indicated by the line 10 so that there will be water in the lower portion of the container 9 and on a level with the water 85 in the radiator 4 under normal condition which is made possible by the provision of the connecting pipe 8, and the connecting pipe 7, which connects the upper interior portion of the radiator 4 with the upper interior portion of the container 9, and maintains an equal atmospheric or steam condition 90 in the upper interior portions of the radiator 4 and container 9. Within the radiator 4 and the container 9 and above 100 the normal water level 10, I introduce and maintain therein a body or quantity of liquid fuel indicated by the line 11 and which liquid fuel flows on top of the water 10 and having the same level in the radiator 105 4 and the container 9 which is also made possible by the connecting pipe 8. Suitably secured in the upper interior portion of the container 9 is the spider or frame 12 provided centrally thereof with the guide or 110 hub 13 through which is slidably mounted the stem 14 of the valve 15, preferably a

needle valve, the lower end of the valve stem 14 being threaded or otherwise secured in the threaded boss 16 centrally disposed in the top of the hollow float 17 which floats in the body of liquid fuel 11. The valve 15 coöperates with a corresponding valve seat 18 preferably formed in the end of the supply pipe 19 which is threaded or otherwise secured in the boss 20 centrally disposed upon the top of the container 9, though the valve seat 18 may be otherwise constructed if desired. The supply pipe 19 is connected to any suitable tank or reservoir (not shown) which may contain any suitable form of liquid fuel such as gasoline, refined petroleum or crude petroleum and the like, and the supply pipe 19 may be connected by a branch pipe to any suitable form of water tank or reservoir (not shown) and the pipe leading from the fuel reservoir and water tank supplied with any suitable form of valves so that either fuel or water or both may be fed through the pipe 19 to the container 9, the entrance of which being automatically controlled by the valve 15 actuated by the float 17 which is controlled by the level of the oil 11, or the level of the water 10 as the case may be, for maintaining the fluids within the radiator 4 and the container 9 at their normal height or level therein.

The lower end of the pipe 6 is bent to provide the elbow 21 to which is suitably secured any suitable form of check valve 22 and to the check valve 22 is connected the pipe 23 having its opposite end suitably secured in a wall of the intake manifold 2 of the engine, as at 24, though this end of the pipe 23 may be secured within a wall of the leg of the intake manifold 2 at any suitable point, whereby the gas which has been formed by the steam and heat in the upper portion of the radiator 4 and which has collected in the dome 5 together with a suitable proportion of steam will be drawn from the steam dome 5 to the intake manifold 2 by the suction of the engine and there united with the normal gas from the carbureter 3, the additional gas as well as the ordinary gas being carried to the cylinders of the engine in a humidified condition and more efficient for the operation of the engine.

Where necessary a gasket is provided between the filler cap 25 and the filler plug or steam dome 5 so as to make the radiator 4 and the water cooling system of the engine air tight and to prevent the ingress of air into the upper portion of the radiator which would destroy the vacuum created therein by the suction of the engine and thereby seriously affect the efficiency of the invention.

The operation of the invention will be briefly described as follows:

65 Assuming the engine to be running, the

valve 15 and float 17 will be approximately in the position shown in Fig. 2 for feeding the additional fuel to the container 9 and the radiator 4 as the vaporized fuel or gas and the steam which has collected or been drawn in the steam dome 5 is being conveyed through the pipe 6, the check valve 22, the pipe 23 and into the intake manifold 2 by the suction of the engine and in which manifold 2 the additional vaporized and humidified vapor or gas mixes with the ordinary gas which has been drawn through the carbureter 3 and proceeds to the engine cylinders in a more thoroughly gasified, homogeneous and humidified condition. 70 This operation continues during the running of the engine and by the employment of the invention a larger quantity of the cheaper grades of oils such as refined petroleum, crude petroleum and the like can 80 be employed and thereby materially reduce the cost of running the engine. However, when the engine is stopped and the water and oil become cool and contracted their level will be below normal and the valve 15 85 will be automatically unseated and the additional fuel oil or water or both, as the case may be, will be replenished until the same reaches a sufficient level for automatically closing the valve 15 and cutting off the supply of the additional fuel or water, so that when the engine is again started there will be a full complement of additional fuel and water within the radiator 4 and container 9. 90

It will be seen that by the employment of 100 my invention that a greater quantity of oils of lesser volatility can be used in conjunction with a lesser quantity of oils of greater volatility with efficient results and at the same time the combined oils are supplied to 105 the engine in the form of gas in such a condition that danger of carbonization of the working parts of the engine is eliminated.

Having described my invention, what I claim as new and desire to secure by Letters 110 Patent, is:—

1. The combination with an internal combustion engine and an air tight water cooling system thereof having a water level, of means for withdrawing water and fuel vapor from said system above said water level and delivering it to the intake of the engine, and means for supplying liquid fuel to be vaporized to said system at said water level to be vaporized at the level of the water so 115 to pass through said means with the water vapor to the engine intake.

2. The combination of an internal combustion engine and an air tight water cooling system having a water level, of means for withdrawing water and fuel vapor from said system above said water level and delivering it to the intake of the engine, a liquid fuel container at said water level communicating with the space above said level, 120

and means for delivering liquid fuel to be vaporized to said container, said container being arranged to be heated by the hot water in said system at the water level.

- 5 3. The combination with an internal combustion engine and an air tight water cooling system having a water level, of a liquid fuel container having its lower portion communicating with said system near the water level
- 10 and having its upper portion communicating with the space above said water level, means for withdrawing water and fuel vapor above said water level and delivering it to the intake of the engine, and means for
- 15 supplying liquid fuel to be vaporized to said container.

4. The combination with an internal combustion engine and an air tight water cooling system having a water level, of a liquid fuel
- 20 container having pipes communicating with

the lower and upper portions thereof and connected to said system with the lower pipe near the water level and the upper pipe communicating with the space above the water level, means for withdrawing water and fuel vapor from the space above the water level and supplying it to the intake of the engine, a pipe for delivering liquid fuel to be vaporized into said container, and means controlled by the level of liquid fuel in said

25

30 container for opening and closing said liquid fuel pipe to maintain the liquid fuel level in said container.

In testimony whereof I have signed my name to this specification in the presence of

35

two subscribing witnesses.
